UNITED STATES PATENT OFFICE.

MELVIN L. STONE, OF LAWRENCE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

1,369,484.

Specification of Letters Patent. Patented Feb. 22, 1921.

Application filed November 26, 1919. Serial No. 340,890.

To all whom it may concern:

Be it known that I, MELVIN L. STONE, a citizen of the United States, residing at Lawrence, in the county of Essex and State 5 of Massachusetts, have invented an Improvement in Feeler Mechanism for Looms, of which the following description, in connection with the accompanying drawings, is a specification, like characters on the drawings representing like parts.

This invention relates to feeler mechanism for looms whereby the operative condition of the loom is changed or filling replenished when the filling in the shuttle is found to be 15 substantially exhausted on a detecting beat.

Various attempts have been made with more or less success to effect replenishment of filling when that in the active shuttle reaches a degree of substantial exhaustion 20 such that a minimum amount of waste shall remain upon the filling carrier when a change is called, and yet sufficient in quantity to lay with proper tension the last or final pick prior to change. Some of these 25 feeler mechanisms have measured or calipered the diameter of the filling mass on the filling carrier, and have effected a change in the loom operation or replenishment of filling when the diameter of the yarn mass has 30 reached a predetermined amount. In other cases the feeler member has been mounted for movement longitudinally of the shuttle along the surface of the filling carrier when, 35 on a detecting beat substantial exhaustion of filling is detected; and in still other cases the operative or inoperative condition of the feeler mechanism has been made dependent upon the passage or non-passage of air through or between the feeler member and 40 a surface within the shuttle. The present invention differs from all of these, and has for one of its objects to provide a feeler mechanism which shall be sensitive both to the presence and absence of a working supply 45 of filling in the shuttle, and upon occurrence of substantial exhaustion thereof, shall detect the fact by rearward movement of a feeler member with the lay or shuttle as it goes back after a detecting beat.

50 In carrying the invention into practical effect, the feeler member is provided with what may be conveniently designated a vacuum cup which, when the filling is substantially exhausted on a detecting beat, will 55 cling to the surface of the filling carrier or

bobbin within the shuttle and be moved rearwardly by the suction between such surface and vacuum cup as the lay goes back after a detecting beat. This rearward movement of the feeler member which is due to the 60 suction between the surface within the shuttle and the vacuum cup, is utilized, in the present invention, to set in action a train of mechanisms whereby the operative condition of the loom is changed or filling replenished. When a working supply of filling is 65 present in the shuttle, however, on a detecting beat, the vacuum cup will be engaged by the mass of filling, but owing to the porous nature thereof or the openings between the coils, air is permitted to pass into the 70 vacuum cup as the lay goes back after a detecting beat, so that the feeler member does not cling to the filling carrier or bobbin, and consequently, is not moved rearwardly 75 by suction between such vacuum cup or filling carrier or bobbin when a working supply of filling is present in the shuttle on a detecting beat.

The feeler member provided with the suction cup tip is supported in its normal feeling position with capacity for frontward movement, and yielding means is provided to permit the feeler member to move rearwardly of its normal feeling position when, 85 on a detecting beat, filling is substantially exhausted.

The vacuum cup which constitutes the tip of the feeler member, in the present invention, may be variously contrived, but is preferably formed as hollow rubber or other flexible cup mounted upon the end portion of the feeler member, and its edge portions are shaped to conform substantially with the surface of the filling carrier or bobbin to 90 further insure a proper suction grip between the vacuum cup and filling carrier or bobbin when the filling is substantially exhausted.

The above and other novel features and 100 new combination of parts will hereinafter be described in connection with the accompanying drawings which form one good practical embodiment of the invention.

In the drawings:—

Figure 1 is a plan view of the feeler side of a loom, showing more particularly the general relation between the feeler mechanism and the shuttle, lay and associated parts;

105

110

Fig. 2 is an enlarged detached perspective view showing the mounting of the feeler member and feeler carrier;

Fig. 3 is a detached detail perspective view 5 of the vacuum cup tip of the feeler member, some of the material of the tip being broken away to show the parts beyond;

Fig. 4 is a longitudinal section of the feeler mechanism along the line 4—4 of Fig. 10 1, the parts being shown on an enlarged scale, and their relative positions indicated when a working supply of filling is present in the shuttle on a detecting beat; and

Fig. 5 is a corresponding sectional view to 15 that of Fig. 4, the relation of the parts being shown when the feeler member is moved rearwardly by the suction between the vacuum cup and filling carrier or bobbin as the lay moves back after a detecting beat.

20 The loom frame 1 has the usual transverse or rock shaft 2 mounted thereon, as indicated in Fig. 1. The rock shaft 2 is connected to a train of mechanism for effecting replenishment of filling, in the present instance, which 25 being common and well known in the art, is not herein illustrated and described. Rising from the rock shaft 2 is the arm 3 carrying the latch 4, the rear end portion 5 of which is adapted to be engaged by an operating member 6 when the end 5 is in the path of movement of the operating member. The operating member 6 may be any convenient part of the loom which has regular related movements with other parts, and in the present 30 instance, is shown as an arm connected to the weft hammer or cam follower. Pivotally mounted on a bracket 7 rising from the machine frame or the shipper stand 8 is a transmitter 9 one end 10 of which projects 35 under the latch 5, in the present instance, the construction being such that should the end 10 of the transmitter 9 be raised, it will correspondingly lift the end 5 of the latch into the path of the operating member 6, and 40 effect a rocking movement of the transverse shaft 2 and replenishment of filling, as usual.

45 The lay 10 is provided with the usual shuttle-box 11, and the front wall of the shuttle-box is provided with an opening 12 adapted 50 to register with the corresponding opening 13 in the adjacent wall of the shuttle 14 when the latter is in the detecting box, as indicated in Fig. 1. The shuttle 14 carries the filling carrier or bobbin 15 on which the filling 55 is wound.

60 The feeler member is appropriately supported upon a feeler carrier with capacity for frontward movement. Various forms of carriers have become employed in feeler looms, but in the present instance, as a preferred form, the feeler carrier comprises a slide 16 which is mounted in a feeler stand 17 for reciprocating movement toward and from the front of the loom. A spring 18 interposed between the collar 19 and the front

70 wall 20 of the feeler stand, normally maintains the feeler carrier 16 in its rearward position, with the collar 19 resting against the stop 21, as indicated in Fig. 5.

75 The feeler carrier has a stem portion 22 which extends frontwardly through an opening in the feeler stand, and its rear portion is formed to support the feeler member for movement relative to and also with the feeler carrier. In the present instance of the invention, the rear portion of the feeler carrier 16 is provided with the rearwardly extending side arms 23 which terminate at their rear portions in the head 24, the construction being such that frontward pressure against the head 24 will move the feeler carrier frontwardly against the yielding tension of its spring 18.

80 Mounted upon the feeler carrier for movement toward and from the front of the loom relative to the feeler carrier is the feeler member provided with a vacuum tip.

85 In the present instance, the feeler member comprises the arm or slide 25 which is mounted between the rearwardly projecting portions 23 of the feeler carrier. The feeler member or slide 25 passes through a bridge or guide 26 mounted upon the feeler carrier, as indicated in Fig. 2, and a spring 27 mounted upon the feeler member or slide 25 and 90 interposed between the bridge 26 and a collar 28 fastened to the feeler member or slide 25, normally holds the feeler member 25 in a frontward position relative to the feeler carrier, a stop being provided for limiting such 95 frontward movement, as will presently appear.

100 The feeler member or slide 25 carries a cam member which, when the feeler member is moved relative to the feeler carrier in a rearward direction beyond the normal feeling position of the feeler member, actuates a train of mechanism to effect replenishment of filling.

105 In the present instance, the feeler member 25 has rising therefrom an arm 29 surmounted by a cam member 30 having a slot 31 whose frontward portion 32 is inclined as indicated in Figs. 2, 4 and 5.

110 The cam member 30 passes through a guideway formed in a lug 33 rising from the feeler stand, which thereby serves to guide the cam member 30 in its frontward and rearward movements.

115 The cam member 30 may, if desired, be further guided by the top supporting surface of the feeler stand 17 which is slotted as indicated at 34 for the passage 120 of the arm or riser 29.

125 The slot 31 in the cam member is engaged by an end portion of the transmitter 9, as indicated in Figs. 2, 4 and 5, the construction being such that when the parts are in normal feeling position, as indicated in Fig. 2, the end of the transmitter 9 rests in the slot 31 near the entrance to the inclined or deflected portion 32 of the slot.

130 As hereinbefore indicated, the feeler mem-

ber, in the present invention, is provided with a vacuum cup which may be variously contrived, but which, in the present instance of the invention, is formed of yielding material such as rubber or the like, and is connected to the feeler member 25 by the collar portions 35, as indicated in Fig. 4. A portion of the feeler tip 36 preferably extends through an opening in the head 24 of the 5 feeler carrier, and is provided with a shoul- dered portion 37 which, under the action of the spring 27 is maintained normally against the rear face portion of the head 24, but with permissive movement rearwardly away from the head 24 against the tension of the 10 spring 27.

The vacuum tip of the feeler member 15 preferably has its contacting edge portions shaped to conform to the general contour of the filling carrier or bobbin which they engage when the filling is substantially exhausted. In the present instance, the 20 vacuum feeler tip has the upper and lower straight edges 38 which engage at opposite 25 sides of the axis of the filling carrier or bobbin. The side walls of the vacuum tip are concave as at 39 to conform to the contour of the filling carrier or bobbin, and the 30 vacuum tip is provided with the hollow or cup-like portion 40.

While the shoulders 37 constitute a good 35 form of stop for limiting the forward impulse of the spring 27 upon the feeler member, it is obvious, of course, that any other 40 form of stop which will effect this purpose may be employed, the conditions being that when the feeler member and feeler carrier are in their normal feeling position, as indicated in Figs. 1 and 2 the feeler carrier will 45 be held yieldingly in its rearward position by the spring 18, which forces the collar 19 against the stop 21, while the feeler member will be held yieldingly forward relative to the feeler carried by the light spring 27, which holds the stop 37 against the rear 50 face of the head 24.

When a working supply of filling is 55 present in the shuttle on a detecting beat, as indicated in Fig. 4, the yielding edge portions 38 of the vacuum cup constituting the feeler tip, will engage the filling mass and cause the feeler member and perforce the feeler carrier to be moved forwardly. During this time the end of the transmitter 60 9 will remain in the substantially horizontal portion 31 of the cam slot in the cam member 30 as the latter moves forwardly. When this action takes place, the concave 65 side edges 39 of the vacuum tip which are formed in the arc of a circle of smaller radius than the radius of the cylindrical mass of filling on the filling carrier or bobbin, will not cling closely to the mass of filling, and as indicated in Fig. 4, a sufficient 70 opening or clearance will be afforded for

entrance of air into the vacuum cup or tip. Air will also be permitted to circulate into and out of the vacuum tip along the straight edge portions 38 of the vacuum tip on account of the space between the coils of filling 75 which are engaged by the edges 38. Thus, when the feeler carrier and feeler member have been moved forwardly as hereinbefore described, and as indicated in Fig. 4, and the lay therefor retreats, the feeler 80 member and feeler carrier under the action of the spring 18, will follow the lay until the feeler member reaches its normal feeling position with the collar 19 against the stop 21, and as the lay further retreats, the feeler 85 member 25 will remain in its feeling position as defined by the spring 18 and 27, because no vacuum will have been formed in the vacuum cup-like tip. When, however, filling is substantially exhausted on a detecting beat, and the surface of the bobbin or filling carrier engages the edges of the 90 vacuum tip, as indicated in Fig. 5, the parts will again be moved forwardly, and the vacuum tip will again be collapsed to some degree. When the lay goes back or retreats, under the conditions noted, the edge portions 38 and 39 of the vacuum cup form an 95 air-tight joint between the surface of the filling carrier or bobbin and the collapsed vacuum cup, with the result that when the collar 19 meets the stop 21, as indicated in Fig. 5, on the backward movement of the lay, the suction or vacuum in the vacuum 100 cup will cause the cup to cling to the bobbin or filling carrier and follow it against the tension of its light spring 27 as the lay further retreats. This rearward movement of the feeler member 25 relative to the feeler carrier (Fig. 5), causes the inclined or cam portion 32 of the slot in the cam member 30 to pass over the transmitter 9, as indicated in Fig. 5, and lift the latch 4 into the path of the operating member 6, thereby effecting 105 replenishment of filling.

The vacuum cup, as hereinbefore noted, is preferably formed of rubber, or like yielding material, and its edge portions 38 and 39 are made sufficiently thin to yield in response to the pressure upon them by the 115 filling or filling carrier on a detecting beat. The vacuum cup is preferably formed somewhat oblong, as indicated in Fig. 3, that is, its dimensions longitudinally of the filling carrier or bobbin may advantageously be 120 made greater than the dimension transversely of the filling carrier or bobbin.

What is claimed is:—

1. In a feeler mechanism for looms, the combination of the lay and shuttle, a feeler 125 member having a vacuum cup tip, means for supporting the feeler member in normal feeling position to enter the shuttle on each detecting beat, and yielding means permitting further rearward movement of the 130

- feeler member with the lay by the suction between the tip and a surface within the shuttle when the filling is substantially exhausted. 45
5. 2. In a feeler mechanism for looms, the combination of the lay and shuttle, a feeler member that has a cup-like tip, means for supporting the feeler member in a normal rearward position to feel for the filling on 10 each detecting beat, and yielding connections between the said means and the feeler member that permit further rearward movement of the feeler member relative to the supporting means by the suction between 15 the cup-like tip and a surface within the shuttle as the lay goes back when the filling is substantially exhausted. 50
3. In a feeler mechanism for looms, the combination of the lay and shuttle, a feeler member having a rubber cup-like tip the 20 edge portions of which are adapted to conform to a surface within the shuttle on a detecting beat, and means for supporting the feeler member for rearward movement 25 with the lay by the suction between the cup-like tip and a surface within the shuttle when the filling is substantially exhausted on a detecting beat. 55
4. In a feeler mechanism for looms, the combination of the lay and shuttle, a feeler member having a flexible cup-like tip opening rearwardly and mounted for rearward movement with the lay by the suction between the tip and a surface within the shuttle when the filling is substantially exhausted. 60
5. In a feeler mechanism for looms, the combination of the lay and shuttle, a feeler member having a cup-like tip opening rearwardly and adapted to engage a surface within the shuttle on each detecting beat 65
- and supported for rearward movement with the lay by the suction between the tip and surface within the shuttle when the filling is substantially exhausted. 70
6. A feeler having a cup-like tip shaped to conform and adhere to the surface of a filling carrier in the shuttle when the filling is substantially exhausted on a detecting beat. 75
7. A feeler having a flexible cup-like tip shaped to conform and adhere to the surface of a filling carrier in the shuttle when the surface of the filling carrier is exposed on a detecting beat. 80
8. A feeler having a vacuum cup-tip, the edge portions of which are flexible and shaped to conform to the surface of a filling carrier or bobbin in the shuttle when the filling is substantially exhausted on a detecting beat. 85
9. In a feeler mechanism for looms, a feeler member having a rubber vacuum cup tip shaped to conform to a surface within the shuttle on a detecting beat. 90
10. In a feeler mechanism for looms, a feeler member having a vacuum cup tip, the side edge portions of which are concaved to fit a surface within the shuttle. 95
11. In a feeler mechanism for looms, a feeler member having a vacuum cup tip provided with two opposite straight edge portions. 70
12. In a feeler mechanism for looms, a feeler member having a hollow rubber tip open at its free end and provided with two opposite straight edge portions and two opposite concaved edge portions. 75

In testimony whereof I have signed my name to this specification.

MELVIN L. STONE.
